UNITED STATES PATENT OFFICE.

ROBERT B. CAMPBELL, OF LONG ISLAND CITY, NEW YORK, ASSIGNOR, BY MESNE ASSIGNMENTS, TO DRY ICE CORPORATION OF AMERICA, OF NEW YORK, N. Y., A CORPORATION OF DELAWARE.

CARBONATOR.

Application filed August 24, 1923. Serial No. 659,122.

This invention relates to siphon bottles and means for charging water in the home to provide home beverages. It consists primarily of a siphon in connection with a 5 charging bottle provided with a safety means for protection to the user.

In the specification like parts are referred to by like numerals in the several views of the accompanying drawings, in which:

10 Figure 1 is a side view of a bottle with parts broken away;

Fig. 2 is a longitudinal sectional view of the neck of the bottle, partly in elevation;

15 Fig. 3 is a detailed sectional view on the line 3-3 of Fig. 2;

Fig. 4 is a view of a modified form of siphon head;

Fig. 5 is an enlarged sectional view of the charging valve;

20 Fig. 6 is a detailed sectional view on the line 6-6 of Fig. 5 looking in the direction of the arrows;

Figs. 7 and 8 are detailed views of the valve cup;

25 Fig. 9 is a side elevation of the charging elements applied to the siphon bottle;

Fig. 10 is an enlarged sectional view of the safety valve;

30 Fig. 11 is a sectional view on the line 11-11 of Fig. 10.

Referring more particularly to the drawings the numeral 1 shows a bottle of glass or other similar non-corrosive material covered with a metallic shield. This shield is 35 composed of two parts. A base member 2 and a top 3 seamed together as at 4. The upper member 3 having sight holes 5 therein for a purpose to be later described. Within the metal case or shield 2 and at the bottom 40 thereof is a rubber cushion 6.

Referring to Fig. 2, the upper part of the casing 3 is formed into a neck closely fitting the neck of the bottle 1 and is provided with screw threads 7 and an overlying lip 8 resting on the neck of the bottle. Extending 45 within the bottle is a glass siphon tube 9 which extends close to the bottom of the bottle as shown. The upper end of this tube is secured in a casting 10 fitted with a rubber gasket 11.

An adaptor is secured to the top of the member 3 by means of a screw threaded portion 13, while bearing upon the rubber gasket 11 and firmly clamping it to the neck 55 of the bottle is a depending shoulder 14

which when the adaptor is screwed down tight on the neck of the bottle casing forms a perfect seal to prevent the escape of gas from around the neck of the bottle. The upper end of the adaptor is provided with a 60 screw threaded portion 17 to receive the siphon head 18, said portion 17 being provided with a passage 15, as shown.

The siphon head 18 is provided with a valve 19 and the usual spigot 20. The valve 65 19 and its controlling spring 21 are operated by a lever 22. These elements are of well-known construction but form part of my novel combination.

The means by which the siphon is charged, 70 consists of a valve located in the head of the siphon separate from the valve through which the carbonated water is discharged. This may be formed integral with the head as shown in Fig. 2, or as a separate element 75 as shown in Fig. 4.

Referring particularly to the form shown in Fig. 2, the casing 23 is integral with the siphon head body and is provided with a valve seat 24 carried by a screw plug 25 which is to be tightly screwed into the body of the valve 23 so as to insure a perfect seal and thus prevent the escape of the gas. The plug 25 is provided with a passage 26 and a screw threaded extension 27.

Bearing against the valve seat 24, in a rubber valve 28 held within a valve cup 29. This cup being held against the face of the seat by means of a spring 30. In the wall of the siphon head is a passage 31 leading from the chamber in the valve body 23 to the inner chamber of the siphon valve head.

In the form shown in Fig. 2, the valve cup 29 is provided on its underside with a projecting stud 32 and in the bottom of the valve chamber there is a corresponding stud. In the event that when charging the bottle the gas should be turned on too rapidly this valve will seat, bringing together these two 90 studs and thus act as a check valve to prevent too rapid charging of the bottle.

The valve cup 29 as shown in Fig. 3 is of hexagonal form which when placed in the valve chamber provides passages 33 thus permitting the gas to flow around the cup 100 through the passage 31 and into the bottle of water to be carbonated. A hose 34 is secured to the screw threaded extension 27 of the valve member by means of a swivel 35, as shown in Fig. 9. A similar swivel 36 con- 105

2
neets the opposite end of this hose with the power bottle 37 which contains a supply of carbon dioxide with which the siphon is to be charged.

- 5 Intermediate the ends of the hose a safety valve is provided. This consists of a casing 38 adapted to be secured to a plug 39 carried by a connecting nipple 40. The plug 39 carries the valve seat 41 against which 10 is adapted to seat the valve 42 carried by valve cup 43 held in position by a spring 44. An escape opening 45 is provided in the end of the casing 38. The valve cup 43 is also of angular formation and provides 15 the gas passages 46. 46 is a gas passage through the plug 39.

The power bottle 37 is operated by means of a hand wheel 47. Bottle 37 contains carbon dioxide under high pressure.

- 20 In Figs. 5 to 8 inclusive is illustrated a modified form of charging valve which is not integrally formed with the siphon head and consists as follows:

A casing 50 provided with a screw-threaded extension 51 is adapted to be screwed into the side wall of the siphon head, as shown in Fig. 4. The casing 50 is provided with a valve chamber 52. The upper end of the chamber 52 is threaded at 30 53 to receive a screw plug 54 which carries a valve seat 55. A passage 56 extending through the screw plug, as shown in Fig. 5. The upper end of this plug is provided with a screw threaded nipple 57 for connection with the hose of the charging element. The rubber valve 58 is carried by a valve cup 59 and is normally held in closed position by spring 62. The valve cup 59 is of angular formation in cross section and provided with the gas passages 61 between it and the walls of the chamber 52, as shown in 40 Fig. 6.

Carried by the underface of the cup 59 are lugs 60 which act as stops to prevent said 45 cup from going too far and thus preventing the passage of gas through the opening 63 in the lower extension 51 of the valve casing.

The operation of the device is as follows: The siphon head together with the adaptor 50 is removed from the neck of the bottle. The bottle is then filled with water to a point on a line with the bottom edge of the sight holes 5. The siphon head and the adaptor are then tightly screwed down on the neck 55 of the bottle so that the gasket therein will tightly seal and prevent the escape of the gas. The swivel on the hose is then connected to the stud 27 of the charging valve, the bottle connected by means of swivel 36 60 to the other end.

By means of the hand wheel 47 the valve in the power bottle should be opened very gently at first allowing the gases to enter the siphon very slowly which will give more 65 perfect carbonation. Should the gases be

turned on too full the sudden charge of gas will cause the valve cup 29 to set against the bottom face of the valve chamber and thus prevent excessive charging of the siphon.

The safety valve is so regulated that at a predetermined pressure the valve will lift and permitting the excess gas to escape, prevent over-charging of the siphon and danger of explosion.

From the above, it will be evident that by use of two very simple valves of rugged construction I have achieved a fool-proof system for charging siphon bottles whereby the enormous pressures of 1,000 lbs. per square inch or more, available, in liquid carbon dioxide containers, may be used for charging siphons at home without the slightest danger to the most unskilled operator and requiring only an extreme minimum intelligence for operating in the most effective manner possible. If the operator opens the valve 47 too wide, a small amount of gas will flow into the siphon, the check valve 29 will open too wide, thereby causing its other valve face 32 to close inlet 31. Instantly the pressure will pile up in the pipe 34 and the pressure relief valve 38 will blow. This wastes gas, of course, but it affords safety from possible explosion of the pipe 34 and at the same time the sound of the escaping gas indicates unmistakably to any operator that something has gone wrong and the valve 47 should be partly or completely screwed down. This inevitably 90 results in reducing pressure sufficiently to permit inlet check 32 to open under the action of spring 30, whereupon the safety valve will stop flowing and the regular charging operation will be resumed. In 95 actual practice, this is even simpler than it sounds and is accomplished by the above described novel combination of simple elements.

What I claim is:

1. An apparatus for charging liquids with gas, comprising a dispensing siphon bottle, a detachable head therefor, a passage through said head having an inlet for receivable carbon dioxide gas and an outlet 115 to the interior of the siphon, a valve chamber in said passage, and valve means in said chamber normally closing the inlet, and movable under normal charging pressures to permit passage of the charging gas to the 120 outlet and under excessive charging pressures to close the outlet.

2. In an apparatus for charging siphon bottles of the character specified in claim 1, a charging gas container, a hand control 125 valve therefor, a conduit connecting the gas container to the gas inlet of the siphon bottle, and an automatic pressure relief valve in said conduit.

ROBERT B. CAMPBELL.
